(57) CLAIM

The ornamental design for an adhesive perforated sheet for a printed CD wallet, as shown and described.

DESCRIPTION

FIG. 1 is a top plan view of an adhesive perforated sheet for a printed CD wallet showing our design; and,

FIG. 2 is a bottom plan view of the sheet of FIG. 1. The dashed lines and dotted lines of FIGS. 1 and 2 show recessed lines of weakness as they appear in the top and bottom plan views of the adhesive perforated sheet.
